UNITED STATES PATENT OFFICE.

JOHN E. BELL, OF BARBERTON, OHIO, ASSIGNOR TO THE BABCOCK & WILCOX COMPANY, OF NEW YORK, N. Y., A CORPORATION OF NEW JERSEY.

SUPERHEATER-BOILER.

No. 857,013.

Specification of Letters Patent.

Patented June 18, 1907.

Application filed April 4, 1905. Renewed November 17, 1906. Serial No. 343,931.

To all whom it may concern:

Be it known that I, JOHN E. BELL, of Barberton, Summit county, Ohio, have invented a new and useful Superheater-Boiler, of which the following is a full, clear, and exact description, reference being had to the accompanying drawings, forming part of this specification, in which—

Figure 1 is a diagrammatic cross-section of a superheater boiler constructed in accordance with my invention; Fig. 2 is a sectional side elevation of the same; Fig. 3 is a similar section side elevation showing another arrangement of the superheater; Figs. 4 and 5 are views similar to Figs. 1 and 2 respectively showing a modified form; Fig. 6 is a view similar to Fig. 5 showing another arrangement of this second form; Figs. 7 and 8 are views similar to Figs. 1 and 2 respectively showing a further form; Figs. 9 and 10 are views similar to Figs. 1 and 2 showing a modified form; and Fig. 11 is a modification of the form of Fig. 10.

My invention relates to the class of water tube boilers having longitudinal upper and lower drums with the setting arranged so that the gases pass longitudinally into the drums.

The invention is designed to provide a superheater in the setting of such a boiler, such superheater having one or more drums or chambers with superheating tubes connected thereto.

In the drawings, referring to the forms of Figs. 1 and 2, 2 represents the longitudinal steam and water drum, 3 the corresponding longitudinal mud drum, 4 the front wall, and 5 the rear wall of the setting, 6 the offtake, and 7 the furnace. The furnace in this form is shown as placed below the mud drum and 40 an arch or roof 8 extends over the furnace from side to side, a portion of the length of the mud drum, and is provided with a baffle extension 9 beneath the remaining portion of the drum. This provides ports 10, 10 opening upwardly on each side of the drum 3 at its rear. 11 is a baffle which extends upwardly between the water tubes 12 which connect the steam and water drum with the mud drum, and 13 is a depending baffle extending downward from the upper drum. In this form the second and middle pass of the gases between the baffles 11 and 13 is occupied by inclined superheating tubes 14 which

connect a lower steam drum 15 at one side of the boiler with an upper steam drum 16 at the other side. The steam drum 16 is divided by a partition 17 into two chambers, the steam entering one chamber through pipes 18 leading from the steam and water drum. The steam entering one upper chamber descends 60 through a portion of the tubes 14, thence rises through the other tubes into the other top chamber, and passes out through the outlet 19.

The form of Fig. 3 is similar to that of Figs. 1 and 2, except that the superheater is placed in the third pass of the gases, the water tubes 12^a occupying the first two passes. The superheater tubes 14^a connect the upper drum 16^a with the lower drum 15^a of the superheater, these drums being located on opposite sides of the central plane of the boiler.

In the form of Figs. 4 and 5 the boiler proper is substantially the same as that of Figs. 1 and 2, while the superheater is provided with two upper drums 16^b arranged on opposite sides of the steam and water drum 2^b and connected by two sets of tubes 14^b to the single lower drum 15^b which is between the steam and water drum 2^b and the mud drum 3^b. In this form I have shown the superheater as arranged in the second or middle pass of the gases; while in Fig. 6 the form is the same as that of Fig. 5 except that the superheater is located in the third pass of the gases. In each case the steam may be taken through tubes 18^b from the steam and water drum to one of the upper superheater drums, whence it flows down through one set of superheating tubes to the lower drum 15^b, and thence to the other upper drum 16^b, whence it passes out through the outlet 19^b.

In Figs. 7 and 8 the boiler is of substantially the same type as that shown in Figs. 1 and 2, while the superheater is provided with two upper drums 16^c, and also two lower drums 15^c. Each upper steam drum is connected with its corresponding lower steam drum by superheater tubes 14^c, and steam may be led to one of the upper drums through tubes 18^c. It then passes to the corresponding lower drum 15^c; thence flows through tubes 20 to the other lower drum 15^c, and thence up to the other upper drum having the outlet 19^c. I have shown this super-

heater as located in the middle pass, though it may of course be located either in the middle or third pass.

In Figs. 9 and 10 I show a form similar to 5 that of Figs. 4 and 5, except that the superheater is provided with a single upper drum 16^d between the steam and water drum 2^d and the mud drum 3^d. This superheater drum is connected by two sets of tubes 14^d 15 with two lower steam drums 15^d, the steam entering the upper drum through the tubes 18^d. In Fig. 10 I have shown this arrangement in the middle pass of the gases, while in Fig. 11 I have shown a similar arrangement in the third pass.

The advantages of my invention result from combining the superheater having one or more separate chambers or drums with a water tube boiler having upper and lower 20 longitudinal drums, the gases passing longitudinally of the boiler drums. The baffles are preferably arranged to give the gases up and down passes, and the first pass is preferably entirely occupied by water tubes. 25 An efficient and economical apparatus may thus be provided for forming and superheating steam.

The furnace may be exterior or partly exterior to the setting proper, the superheater 30 may be provided with return bent or U-shaped tubes, the arrangement of the drums and tubes may be varied, and many other changes may be made without departing from my invention.

35 I claim:

1. A boiler having upper and lower longitudinal drums connected by water tubes, means for passing gases longitudinally of the drums, and a superheater in the boiler structure having a chamber or drum separate 40 from the boiler drums and provided with superheating tubes, the boiler having water

tubes between the source of heat and the superheater; substantially as described.

2. A water tube boiler having upper and 45 lower longitudinal drums connected by water tubes, a baffle arranged to give the gases up and down passes among the tubes and longitudinally of the drums, and a superheater located in the boiler setting with water tubes between it and the source of heat, 50 said superheater having a chamber or drum separate from the boiler drums and provided with superheating tubes exposed to the heat of the gases; substantially as described. 55

3. A water tube boiler having longitudinal upper and lower drums connected by water tubes, baffles arranged to give the gases up and down passes longitudinally of the drums and among the water tubes, and a superheater forming at least the major portion of the heating surface in a pass back of the first 60 pass of the gases, said superheater having a drum or chamber separate from the boiler drums and provided with superheating tubes; 65 substantially as described.

4. A water tube boiler having longitudinal upper and lower drums connected by water tubes, baffles arranged to give at least three 70 up and down passes to the gases longitudinally of the drums, and a superheater forming at least the major portion of the heating surface in a pass in the rear of the first pass, said superheater having a drum or chamber separate from the boiler drums and provided with 75 superheating tubes; substantially as described.

In testimony whereof, I have hereunto set my hand.

JOHN E. BELL.
